CLAIM

The ornamental design a skincare bottle, as shown and described.

DESCRIPTION

FIG. 1 is a perspective view of the skincare bottle according to the present disclosure;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the drawings are included for the purpose of illustrating the portions of the skincare bottle that form no part of the claimed design.
